FEELER MECHANISM FOR LOOMS.

1,388,210.

Specification of Letters Patent. Patented Aug. 23, 1921.

Application filed April 7, 1920. Serial No. 372,007.

To all whom it may concern:

Be it known that I, ISAAC SNOW, a citizen of the United States, and a resident of Lawrence, county of Essex, and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms.

Mechanisms of various types have been devised for either replenishing the filling or stopping the loom when the filling in the shuttle becomes substantially exhausted. In some of these prior types of feeler mechanisms, the feeler has been formed to measure or caliper the diameter of the filling or filling carrier, and when the diameter has reached a predetermined dimension, a train of mechanism has been set in operation to effect replenishment of filling. In another type of feeler mechanism, the feeler has been mounted for lateral displacement in a direction longitudinally of the shuttle by the forward pressure upon the feeler when filling has been substantially exhausted on a detecting beat. The present feeler mechanism differs from either of these types, and comprises a feeler which is mounted for displacement in a direction transversely of the filling carrier or bobbin but is held from such transverse displacing movement by engagement with the filling until the filling is substantially exhausted on a detecting beat.

In carrying the invention into practical effect, the feeler mechanism preferably comprises two feelers, each having a tip portion divergently extending to opposite sides of the axis of the filling carrier or bobbin in the shuttle on a detecting beat, so that the effect of the forward pressure is to relatively separate the tip portions of the feelers, but which functional action of the feelers is prevented by engagement of the tip portions of the feelers with the filling until substantial exhaustion thereof.

Another important feature of the invention consists in having the tip portion of the feeler provided with teeth which extend substantially longitudinally of the filling carrier or bobbin in the shuttle, and engage the filling transversely of the coils of the filling on the bobbin. Heretofore it has been the

practice to provide the tip of a feeler with points, teeth, or other character of engaging end which would penetrate between the coils of the wound filling; but in the preferred form of the present invention, the teeth do not penetrate between the coils of the filling, but extend transversely thereof.

The above features of the invention and additional novel combinations of parts will be hereinafter described in connection with the accompanying drawings which show a good, practical form of the invention, wherein:

Figure 1 is a perspective view of the feeler side of the loom having the present invention applied thereto, some of the parts being omitted for clearness of illustration;

Fig. 2 is an enlarged side elevation of the feeler mechanism, some of the parts being shown in section, and indicating the action of the feeler mechanism when a working supply of filling is present in the shuttle on a detecting beat;

Fig. 3 is a view similar to that of Fig. 2, showing the construction of parts when, on a detecting beat, filling is substantially exhausted;

Fig. 4 is an enlarged section on the line 4—4 of Fig. 2, showing the means for transmitting motion from the feeler to the train of mechanism for effecting replenishment of filling when, on a detecting beat, the filling is substantially exhausted; and

Fig. 5 is an enlarged detail of the tip portion of one of the feelers.

The feeler mechanism is suitably supported to enter the shuttle on each detecting beat and feel for the filling within the shuttle. The carrier or support for the feeler mechanism may be variously contrived to position the feeler for entrance into the shuttle on each detecting beat. In the present instance the feeler is supported upon the loom frame for forward and rearward movement, and is adjustably connected to the frame to be positioned for discharging its feeler function.

The loom frame 1 has connected thereto the brackets 2, one at each side of the loom frame, in which is supported the transverse or rock shaft 3 having secured thereto the arm 4. Pivotedly connected to the arm 4 at 5 is the latch 6, the rear end 7 of which is adapted at times to be engaged by an operating member 8. The operating member

- may be on any suitable going part of the loom, and is preferably formed, as usual in this type of loom, by a part connected with the cam follower or weft hammer, the construction being such that when the end 7 of the latch 6 is moved forwardly by the operating member, replenishment of filling or other change in the operative condition of the loom is effected.
- 10 The shipper stand 9 has an arm 10 extending therefrom to which is adjustably connected the support or bracket 11. The adjustable connection may be effected by means of the slot 12 and the adjusting bolt 13. The support or bracket 11 affords one good form of convenient means for sustaining the feeler mechanism, although, as will be evident to those familiar with this character of loom, other forms of supports may be devised.
- 15 Adjustably connected to the bracket or support 11 is the feeler stand or carrier 14 which is provided with the slot 15 through which extends the securing bolt 16, whereby the position of the feeler stand or carrier 14 may be varied as the circumstances dictate.
- 20 The feeler stand or carrier 14 affords one good, practical form of means for supporting the feeler for movement toward and from the front of the loom. In the present instance of the invention, the feeler stand 14 has the front flange 17 and the rear flange 18, in each of which is formed the suitable support for the feeler. The flanges 17 and 18 may be variously contrived, but in the present instance, are shown by upturning the front and rear edge portions of the feeler stand or carrier 14.
- 25 Mounted for reciprocating movement on the stand 14 is the feeler slide 19 which passes through a bearing in the rear flange 18 and extends forwardly through a bearing in the front flange 17. The rear bearing 20 is preferably formed other than circular in cross section, as a convenient means for preventing the feeler from rotating, although of course, other devices might be employed for this purpose. Extending
- 30 frontwardly is the stem 21 which is preferably of circular form in cross section, and is surrounded by a spring 22, the front end portion of which bears against the rear surface of the front flange 17 and the rear end portion of which bears upon the shouldered portion 23 of the feeler slide, the construction being such that the spring 22 normally forces the feeler rearwardly into feeling position. A suitable stop 24 limits the
- 35 rearward movement of the feeler.
- 40 The feeler slide has mounted thereon two feelers, in the illustrated form of the invention, each of which is mounted for movement in a direction transversely of the bobbin or filling carrier in the shuttle. In the

present instance the two feelers 25 and 26 are pivotally supported at 27 and 28 respectively, on the feeler slide 19, and the rear portion or tips of the feelers extend divergently in a direction to receive between them the bobbin or filling carrier, the construction being such that on a detecting beat the forward pressure upon the divergently-extending tip portions of the feelers tends to separate the rear or tip portions of the feelers in a direction extending transversely of the filling carrier or bobbin.

As best indicated in Fig. 1, the tip portions 29 and 30 of each of the feelers 25 and 26 flare rearwardly and diverge, and each is provided with one or more teeth 31 which extend in a direction longitudinally of the filling carrier or surface engaged by the tip portions of the feelers on a detecting beat. The teeth 31 may be variously formed, but are preferably as indicated in detail, Fig. 5, that is, the rear faces 32 of the teeth and the front faces 33 of the teeth are so inclined with respect to each other that they form a biting edge 34, which is adapted to sink into the filling, notwithstanding the fact that the engagement of the teeth with the filling is transversely of the coils thereof.

Where two feelers are used as hereinbefore described, it is desirable that the feelers shall be moved in a direction of relative separation in unison; and to this end the feeler 25 is provided with a toothed segment 35 and the feeler 26 is provided with a toothed segment 36 which are operatively engaged as indicated in Figs. 2 and 3, so that upon movement of either feeler, where two are used, the other feeler will be correspondingly moved in a direction of separation transversely of the bobbin or filling carrier.

The feelers are normally held in closed position, as indicated in Fig. 2, and such relation may be readily effected by a light spring, such as 37, placed between the frontwardly-extended portions of the feelers as indicated in Fig. 2.

From the construction thus far described, it will be apparent that when a working supply of filling is present in the shuttle, and the feelers meet the filling on a detecting beat as indicated in Fig. 2, the tendency of the forward pressure against the outwardly divergent tips of the feelers is to separate the rear or tip portions of the feelers, and such tendency is rendered ineffective by the teeth of the feelers sinking into the working filling transversely of the coils thereof. Under the conditions stated, and as indicated in Fig. 2, the feelers will be moved forwardly on a detecting beat without relative displacement of the feelers transversely of the filling carrier or bobbin. When, however, the filling is substantially exhausted on a detecting beat, the tendency of the feelers to separate at their rear or

tip portions under forward pressure of the surface within the shuttle will no longer be resisted by the teeth engagement of the filling on a detecting beat, and the feelers will be relatively separated as indicated in Fig. 3. Advantage is taken of this separating movement of the feelers, where two are used, to position a train of mechanism for effecting replenishment of filling.

10 In the present instance the feeler stand 14 has rising therefrom the finger 38, to the upper portion of which at 39 is pivotally connected the swinging arm 40. The swinging arm 40 carries a plate 41 which extends frontwardly from the arm 40, as indicated in Figs. 1, 2 and 3. One of the feelers, 25 in the present instance of the invention, has a frontwardly-extending arm 42, the end 43 of which is opposite the plate 41, the construction being such that if the arm 42 of the feeler 25 be depressed by movement of the feeler in a direction transversely of the bobbin on a detecting beat, the end 43 will press upon the plate 41 and turn the swinging arm 40 from the full line position indicated in Fig. 4 to substantially the dotted line position, to thereby effect replenishment of filling.

20 The swinging arm 40 has the downwardly-extending portion 44 to which is connected a transmitter 45 which is utilized to transmit movement of the swinging arm to responsive movement of the latch 6 to place its rear end in or out of the path of movement 30 of the operating member 8. Any suitable type of transmitting mechanism may be employed, but in the present instance of the invention the loom frame has rising therefrom the bracket 46 to which is secured by a bolt 35 47, the arm or support 48, the end portion of which has connected thereto the bell crank lever 49 pivotally supported on the arm at 50 and having an end 51 underlying a portion of the latch 6. The portion of the 40 latch 6 under which the part 51 extends, may be variously formed, but in the present instance it consists of the finger 52 connected to the rear end portion 7 of the latch. The rear end portion 7 of the latch is pivotally connected at 53 to the latch, so that such 45 rear end portion 7 may be raised or lowered by the bell crank lever 49 through the transmitting mechanism described when the feeler is moved in a direction transversely 50 of the bobbin or filling carrier on a detecting beat. The particular form and character of the end 7 of the latch 6 is not of importance in the present invention, except in so far as it should be properly constructed to permit 55 the transmitting mechanism to place the end of the latch in the path of the operating member when filling is substantially exhausted on a detecting beat.

60 In some cases it may not be necessary to use the two feelers 25 and 26, but the two-

feeler form of construction is preferable because it adds to the delicacy and responsiveness of the feeler mechanism to the presence or substantial absence of filling on a detecting beat.

70

The lay 54 is of the usual construction and has the shuttle-box 55 into which the shuttle 56 is thrown or picked. The shuttle 56 carries the bobbin or filling carrier 57 on which is wound the filling 58 by the usual character of filling wind. The front wall of the shuttle-box is provided with an opening 59 and the adjacent wall of the shuttle when in the box, is provided with a similar opening 60, the construction being such that when 80 the shuttle is boxed at the detecting side of the loom, the openings 59 and 60 will register to permit the entrance of the feeler or feelers into the shuttle, as usual in this class of looms.

85

What is claimed is:—

1. In a feeler mechanism for looms, the combination of two feelers mounted for relative separation in a direction transversely of the bobbin by the forward beat, and which are held from such relative separating movement by engagement with the filling until substantial exhaustion thereof, and means which is actuated by the relative separation of the feelers transversely of the bobbin on a detecting beat to effect replenishment of filling.

90

2. In a feeler mechanism for looms, the combination of two feelers mounted for separating movement transversely of the bobbin by the forward pressure on a detecting beat and which are held from such transverse separation by the filling until substantial exhaustion thereof, and means actuated by the separating movement of the feelers on a detecting beat to effect replenishment of filling.

100

3. In a feeler mechanism for looms, the combination of a feeler mounted independently of the lay which has an inclined engaging end portion to meet a surface within the shuttle at one side only of the horizontal plane passing longitudinally of the axis of said surface on a detecting beat and adapted to be further displaced toward the same side of said surface by the forward pressure of said surface against the inclined engaging end but held from displacement transversely of the surface under the forward pressure by engagement with the filling until substantial exhaustion thereof, and means positioned by the movement of the feeler farther to one side of the said plane by the pressure upon the feeler on a detecting beat to effect replenishment of filling.

110

4. In a feeler mechanism for looms, the combination of a feeler having an inclined end portion provided with teeth to engage a surface within the shuttle in a plane above the longitudinal axis of said surface on a 130

120

125

- detecting beat and adapted to be further displaced toward the same side of said surface by the pressure against the inclined end but which prevent movement of the feeler 5 transversely of the surface by engagement with the filling until substantial exhaustion thereof, and means positioned by movement of the feeler transversely of the engaged surface on a detecting beat to effect replenishment of filling.
5. In a feeler mechanism for looms, the combination of a feeler having an inclined end portion provided with teeth extending longitudinally of the shuttle to engage a 15 surface within the shuttle in a plane above the longitudinal axis of said surface on a detecting beat and which prevent movement of the feeler transversely of the surface by engagement with the filling until substantial exhaustion thereof, and means to effect replenishment of filling when the inclined end 20 of the feeler slides transversely over the surface of the filling carrier by the frontward pressure against the inclined end.
25. 6. In a feeler mechanism for looms, the combination of a feeler having an inclined engaging end and which is mounted at the front of the loom independent of the lay for movement transversely of the bobbin or filling carrier by the frontward pressure upon it on a detecting beat and which is held from such transverse movement by the filling until substantial exhaustion thereof, and means actuated by further movement of the feeler 30 transversely of the bobbin or filling carrier in a direction substantially at right angles to the path in which the lay moves to effect replenishment of filling.
7. In a feeler mechanism for looms, a 40 feeler having an engaging tip which is inclined in a direction transversely of the bobbin and provided with teeth which extend longitudinally of the bobbin and slip transversely over the bobbin when filling is substantially exhausted on a detecting beat.
50. 8. In a feeler mechanism for looms, the combination of two feelers having flaring end portions extending transversely of the bobbin within the shuttle and held from separating movement transversely of the bobbin on a detecting beat under the frontward pressure by engagement with the filling until substantial exhaustion thereof, and means for effecting replenishment of filling 55 when the feeler members are separated.
5. In a feeler mechanism for looms, the combination of two feelers having flaring end portions extending transversely of the bobbin within the shuttle and held from separating movement transversely of the bobbin on a detecting beat under the front- 60
- ward pressure by engagement with the filling until substantial exhaustion thereof, a spring normally acting to hold the feelers in closed relation, and means for effecting 65 replenishment of filling when the feeler members are separated.
10. In a feeler mechanism for looms, the combination of two feelers having end portions which are inclined in opposite directions transversely of the bobbin within the shuttle and which are held from separation transversely of the bobbin under the frontward pressure by the filling until substantial exhaustion thereof, and means positioned 70 by separation of the feeler transversely of the bobbin for effecting replenishment of filling.
11. In a feeler mechanism for looms, the combination of two feelers having end portions which are inclined in opposite directions transversely of the bobbin within the shuttle and provided with teeth, and which are held from separation transversely of the bobbin under the frontward pressure by 75 the filling until substantial exhaustion thereof, and means positioned by separation of the feeler transversely of the bobbin for effecting replenishment of filling.
12. In a feeler mechanism for looms, the combination of two feelers having divergently extending tip portions to meet a surface within the shuttle on a detecting beat at each side of the longitudinal axis of the surface and mounted for relative separation 80 transversely of the surface by the frontward pressure, teeth on the tip portions which prevent transverse separation of the tip portions by the frontward pressure by engagement with the filling until substantial exhaustion thereof, and means actuated by separation of the tip portions of the feelers to effect replenishment of filling.
13. In a feeler mechanism for looms, the combination of a feeler carrier mounted for 90 movement toward and from the front of the loom, a feeler mounted on the carrier having a flaring end and for movement in a direction transversely of the bobbin or filling carrier and held from such movement 95 by engagement with the filling on a detecting beat until substantial exhaustion thereof and thereupon sliding transversely over the filling carrier, a forwardly extending arm connected to the feeler, and mechanism 100 actuated by said arm when the feeler is moved in a direction transversely of the bobbin on a detecting beat to effect replenishment of filling.
14. In testimony whereof I have signed my 105 name to this specification.

ISAAC SNOW.
